UNITED STATES PATENT OFFICE.

LÉON EMILE RÉMONDY, OF PARIS, FRANCE.

PERCUSSION FUSE FOR PROJECTILES, AERIAL BOMBS, AND THE LIKE.

Application filed October 21, 1926, Serial No. 148,260, and in France December 17, 1925.

This invention relates to fuses for projectiles and more particularly to percussion fuses for use in projectiles of the types adapted to be fired from a gun or dropped 5 from an aeroplane.

One of the objects of the present invention is to provide an improved fuse of the type disclosed in my Patent Nos. 1,459,075, dated June 19, 1923, and 1,562,054, dated 10 November 17, 1925.

The fuse of the present invention is of the type embodying primer and striker elements that are longitudinally disposed in substantial alignment in the fuse body, the forward 15 one of said elements (preferably the striker) being normally held against movement relative to the rearwardly disposed element (preferably the primer or percussion cap) by suitable means which imparts the movement of the projectile to said forwardly disposed element. Upon impact of the projectile with its objective, the said means is rendered inoperative by a suitable impact transmitting member and the forwardly disposed 20 element is released and the latter now moves with the residual speed v of the impact transmitting member, which speed may be zero if the objective offers sufficient resistance. The projectile, however, with 25 the rearwardly disposed element continues its travel at its speed v whereupon the primer and striker are engaged one with the other with a force which is proportional to one-half m ($V-v$) ^{2} , m being the mass of 30 the forwardly disposed element.

Various forms of the invention are illustrated, by way of example, in the accompanying drawing.

Figure 1 is a sectional elevation of a projectile fuse, according to the invention, the members being shown at rest.

Figure 2 is a corresponding sectional elevation showing the members in the position they occupy at the moment the mechanism 45 operates as a result of an encounter with an obstacle.

Figure 3 is a sectional elevation showing the application of the invention to a projectile of the bomb type, the members being shown at rest.

Figure 4 is a corresponding elevation showing the members in the position they occupy at the moment of operation of the

fuse resulting from impact with an obstacle offering little or a medium amount of resistance.

Figure 5 is a corresponding sectional elevation, showing the operation of the fuse against an obstacle offering considerable resistance.

Figure 6 shows, in sectional elevation, a modified form of the invention applied to a bomb, the members being shown in the position of rest.

Figure 7 shows the operation of this fuse 65 against an obstacle offering little or a medium amount of resistance.

In these figures: A is a fuse body in which the rear element B, preferably the percussion cap, as shown in the drawing, is made 70 to follow the movements of the said fuse body and consequently the movements of the projectile.

The front element of the mechanism, preferably the striker C, as shown in the drawing, is normally held apart from the percussion cap B by a removable member, such as a pin C¹ and if desired a spring C², of the type disclosed in my prior Patent No. 1,459,075, or any other suitable compressible 80 member.

The characteristic feature of this new fuse, is that the mechanism is combined with an impact transmitting member D normally retained on the fuse body or on the projectile, for example by a pin D¹. This member, which, until an obstacle is struck, is tied to the movements of the projectile, is released from the latter under the effect of the impact against the obstacle, through the removal or shearing of the retaining member D¹, and can thus, immediately or after having effected an inward movement into the fuse body transmit to the striker the action produced by the obstacle, that is to say, 85 destroy or reduce the speed of the striker by releasing it from the restraint of the pin C¹.

It goes without saying that the action of the impact transmitting member must be 100 such that it cannot, in any event, cause the two elements of the mechanism to meet. The striker which, till then, was advancing with the speed V of the projectile, takes up a speed v which is considerably lower or is 105 zero, according to the degree of resistance

offered by the obstacle encountered. On the other hand, the percussion cap B continues to travel with the speed V of the projectile, the latter not having been immediately stopped by the obstacle or at least having its speed very much less retarded than the impact transmitting member D and the striker C. If m is the mass of the striker, an impact will be produced between the said retarded or stopped striker and the percussion cap, the force of which impact will be a function of $1/2 m (V-v)^2$.

In the example shown in Figures 1 and 2, that is to say, in the case of the application of the fuse to a projectile which is to be fired against obstacles of small resistance, such as the envelopes of balloons or the wings of aeroplanes, the impact transmitting member D may be very light, and may consist, for example, of a thin metal cup presenting to the obstacle a very wide contact surface; this cup may be normally held on the fuse body A by a pin D¹ or by a spring D² causing a flange d provided on the said cup to bear against a shoulder a of the fuse. If desired both the pin D¹ and a weak spring D², or any other compressible member, may be used.

Under the action of an impact with an obstacle, even a very light one, such as the fabric of an aeroplane, the cup D, which may be made to project slightly over the fuse body A will be stopped, so that its speed which till then was the same as the speed V of the projectile, will be immediately reduced to a value v , equal or approximately equal to zero, while the projectile continues its movement at the speed V, which causes the pin D¹ to be sheared and the spring D² to be compressed. As soon as the cup D, with the remaining part of the pin D¹, or with its end, strikes the striker C, the pin C¹ is sheared, which renders the striker C independent of the fuse body A. The striker is then in its turn retarded or stopped, while the projectile continues its forward movement, thus allowing the striker and percussion cap to meet with a force which is a function of $1/2 m (V-v)^2$, as mentioned above.

While the fuse is extremely sensitive when the speed V of the projectile is high it cannot operate in the event of the projectile remaining in the bore of the gun, which stoppage at the same time destroys or retards the speed of advance of the percussion cap B and of the striker C, as the operation cannot take place under the action of the mass of the striker alone. As mentioned above, the impact between the cup D and the striker C cannot directly produce the operation of the mechanism. This impact has simply caused the striker to penetrate slightly into its lodgment, the distance thus travelled being much less than is sufficient

to bring the striker into contact with the percussion cap.

With regard to the fuse described and illustrated in U. S. Patents Nos. 1,459,075 and 1,562,054, the new fuse presents the advantage of cutting out the use of a container for the whole of the striker and percussion cap by substituting for this container a light impact transmitting member D.

Instead of separate removable members, C¹ for the retention of the striker, and D¹ for the retention of the impact transmitting member, it would be possible to employ a single removable or displaceable member, such as an ordinary pin passing through the whole of the striker C and the cup D. First a shearing of the pin would be produced under the action of the blow received by the transmitting member, then a further shearing for the release of the striker.

In order to adapt the fuse forming the subject of the invention for use in a bomb, it is sufficient to transform the suspension member of the bomb into an impact transmitting member. Figures 3 to 5 inclusive show such an embodiment of the invention. There is again a rear element, preferably the percussion cap B, stationary in the fuse body A², and a front element, preferably the striker C, normally held on the fuse body by a displaceable member such as a pin C¹ or embodied by means such as a pin C¹ and a spring C, but if desired the pin C¹ may be omitted. The impact transmitting member will in this case be formed by the rod E of the suspension hook.

Any outward movement of the hook will be rendered impossible, for example by a small screw-threaded sleeve F screwed into the fuse body A², while normally any inward movement such as results from impact against an obstacle, will be prevented by a washer E¹ held by its rim between the sleeve F and a nut E² screwed on to the rod E.

An additional safety device, which will only be displaced the moment the bomb is dropped may, in the known manner consist of a collar G interposed between a projecting base e formed on the suspension hook and the front edge or face of the fuse body A², this collar, which is made of two parts, being adapted to open for its ejection or its retention on the aircraft, either under the action of the fall of the projectile, or under the action of a pull exerted by hand or mechanically on the collar itself.

As shown in Figure 4, if the bomb, ejected after the disengagement of the safety collar G, falls on to an obstacle offering a medium or small amount of resistance, the washer E¹ is sheared, which enables the suspension hook and its rod, the movement of which is retarded by the shock, to penetrate into the fuse body and to strike the rod of the striker C, thus producing the release of the latter,

on account of the fact that the pin C^1 is sheared. The projectile continues its movement, carrying along the rod and the suspension hook as soon as the base piece e has 5 reached the fuse body. Meanwhile the striker C , released from the projectile retains its retarded or zero speed so that an impact is produced between the latter and the percussion cap B , which advances with 10 the speed of the projectile.

In the event of an impact against an obstacle offering considerable resistance (Fig. 5) the impact between the percussion cap B and the striker C which is retarded or 15 stopped, will take place during the crushing of the projecting part of the suspension member.

In the example shown in Figures 6 and 7, the front element of the mechanism which 20 consists preferably of the striker C^a , is lodged in a cavity at the rear end of the rod E^a and is normally retained withdrawn in this cavity by a spring C^2 . When an obstacle offering small or medium amount of resistance is encountered, the impact transmitting suspension member, after having sheared the retaining washer E^1 , strikes against the bottom of the lodgment a formed in the fuse body A^1 . From this moment, the 25 said suspension member is carried along by the projectile, whilst the independent striker compresses by its inertia, the spring C^2 and projects out of its lodgment in the rod E^a , which permits the percussion cap B to strike 30 it with a force which is a function, as in the preceding example, of $\frac{1}{2} m (V-v)^2$.

In the form of construction shown in Figures 3 to 5, the suspension member which forms the impact transmitting member, may, 40 of course, comprise an extension which is in contact or nearly in contact with the rod of the striker, in such a manner as to render more rapid the shearing of the pin C^1 , as soon as the inward movement of the suspension member is produced, after the shearing 45 of the washer E^1 .

Having now particularly described and ascertained the nature of my said invention and in what manner the same is to be performed I declare that what I claim is:—

1. A percussion fuse for a projectile comprising a fuse body, primer and striker elements arranged in front and rear positions in said body, the rearward one of said elements being immovably secured to said body, a resilient member intermediate said elements, means normally holding said front element from movement relative to said rearward element, said means being adapted to transmit the movement of said body to said front element, an impact transmitting member carried by said body, and means normally preventing movement of said impact member relative to said body, the impact of 60 the projectile with an objective resulting in 65

rendering said last named means ineffective and permitting movement of said impact member to render said first named means inoperative.

2. In a fuse for projectiles of the type embodying a fuse body and primer and striker elements longitudinally disposed in substantial alinement in said body, the rearwardly disposed one of said elements being fixedly secured to the fuse body and the forwardly positioned one being slidably mounted therein, means normally preventing relative movement between said elements, an impact transmitting member slidably carried by said body and having a portion extending outwardly from said body, and means normally holding said impact member against movement relative to said body, the impact of the projectile with its objective acting to render said last named means inoperative and acting through said impact member to render said first named means inoperative.

3. A fuse of the type embodying a fuse body and primer and striker elements longitudinally disposed in substantial alinement in said body, the rearwardly positioned one of said elements being fixedly secured to said body and the forwardly disposed one being adapted for sliding movement in the body, an impact transmitting member carried by said body, and means normally preventing movement of said impact member and the forwardly disposed one of said elements relative to said fuse body, the impact of the fuse with an obstacle acting to render said means inoperative and to produce engagement of said elements.

4. In a bomb fuse of the type embodying a fuse body and primer and striker elements longitudinally disposed in substantial alinement in said body, means normally preventing relative movement between said elements, an impact transmitting member carried by said body, means preventing movement of the impact member outwardly from the body, and frangible means for preventing movement of the impact member inwardly relative to the body, the impact of the bomb with an obstacle acting to render said first named means and the frangible means inoperative.

5. In a bomb fuse of the type embodying a fuse body and primer and striker elements longitudinally disposed in substantial alinement in said body, means normally preventing relative movement between said primer and striker elements, a suspension hook carried by said body, and frangible means normally preventing movement of the hook relative to the body, the impact of the hook with an obstacle acting to render said first named means and said frangible means inoperative and to permit relative movement between the primer and striker elements.

6. In a fuse of the type embodying a fuse

- body and primer and striker elements longitudinally disposed in substantial alignment in said body, the rearwardly disposed one of said elements being fixedly secured to the fuse body and the forwardly positioned one of said elements being adapted for sliding movement in said body, yielding means normally preventing relative movement of the forwardly positioned element relative to the rearwardly positioned element, a suspension hook carried by the fuse body and projecting therefrom, and a frangible disk for preventing movement of the hook inwardly relative to the fuse body, impact of the hook with an obstacle acting to render said disk and yielding means inoperative, whereby movement of the hook and forwardly positioned element relative to the fuse body is permitted.
7. In a fuse of the type embodying a fuse body and primer and striker elements longitudinally disposed in substantial alignment in said body, the rearwardly disposed one of said elements being fixedly secured to the fuse body and the forwardly positioned one of said elements being adapted for sliding movement in said body, yielding means normally preventing relative movement of the forwardly positioned element relative to the rearwardly positioned element, a suspension hook carried by the fuse body and projecting therefrom, and a frangible disk for preventing movement of the hook inwardly relative to the fuse body, impact of the hook with an obstacle acting to render said disk and yielding means inoperative, whereby movement of the hook and forwardly positioned element relative to the fuse body is permitted.

gitudinally disposed in substantial alignment in said body, the rearwardly disposed one of said elements being fixedly secured to the fuse body and the forwardly positioned one being adapted for sliding movement in the fuse body, an impact transmitting member carried by said fuse body, the forwardly positioned one of said elements being mounted in said impact member, yielding means normally preventing movement of the forwardly positioned element relative to said impact member and the rearwardly positioned element, frangible means normally preventing movement of the impact member inwardly relative to the fuse body, and means for preventing movement of the impact member outwardly relative to the fuse body.

In testimony whereof I have signed this specification.

LÉON EMILE RÉMONDY.
